US00D610754S

(12) **United States Design Patent**
White

(10) **Patent No.:** US D610,754 S
(45) **Date of Patent:** ** Feb. 23, 2010

(54) **HOOF NIPPERS WITH REPLACEABLE BLADE**

(75) Inventor: **Valor P. White**, Farson, WY (US)

(73) Assignee: **Bud's Horseshoeing Equipment Inc.**,
Blackfoot, ID (US)

(**) Term: **14 Years**

(21) Appl. No.: **29/321,592**

(22) Filed: **Jul. 18, 2008**

(51) **LOC (9) Cl.** 30-99

(52) **U.S. Cl.** D30/158

(57) **CLAIM**

What is claimed is the ornamental design for hoof nippers with replaceable blade, as shown and described herein.

DESCRIPTION

FIG. 1 is a side view of the hoof nippers with replaceable blade in accordance with my invention;

FIG. 2 is an opposing side view thereof;

FIG. 3 is a top view thereof;

FIG. 4 is a bottom view thereof;

FIG. 5 is a front view thereof;

FIG. 6 is a rear view thereof;

FIG. 7 is a side perspective view thereof; and,

FIG. 8 is a side perspective view of the hoof nippers with replaceable blade in an opened position.
